ROTARY SCALING DEVICE

Olaf Nedland Pedersen, 1100 Haring Road, Metairie, La.

Filed Aug. 19, 1959, Ser. No. 834,691

5 Claims. (Cl. 29—81)

The present invention relates to a rotary scaling device for removing rust and paint from surfaces, such as those of a ship, prior to repainting.

The primary object of the invention is to provide a rotary scaling device which is portable, strong, safe to operate, light of weight, and which has the drive motor therefor directly connected thereto.

Another object of the invention is to provide a rotary scaling device having a plurality of universally mounted hammers constructed to permit the hammers to move outwardly from center under centrifugal force of rotation of the scaling device.

A further object of the invention is to provide a rotary scaling device of the class described above in which the hammers are mounted for rotation on their own axis and can be readily removed from the scaling device for repair or replacement as required.

A still further object of the invention is to provide a rotary scaling device of the class described above which is inexpensive to manufacture, simple to use and which effectively performs the scaling function desired.

Other objects and advantages will become apparent in the following specification when considered in light of the attached drawings, in which:

Figure 1 is a side elevation of the invention shown partially broken away and in section for convenience of illustration; and

Figure 2 is an end elevation of the invention from the scaling tool end.

Referring now to the drawings in detail wherein like reference characters indicate like parts throughout the several figures, the reference numeral 10 indicates generally a rotary scaling device constructed in accordance with the invention.

The rotary scaling device 10 includes a small electric drill motor 11 having a hand grip 12 and a trigger-actuated switch 13 controlling the operation of the motor 11. The motor 11 includes a conventional gear box and drive to provide the correct drive speed for the scaling device 10. The motor 11 at the end thereof opposite the hand grip 12 is provided with an externally threaded circular boss 14 through which extends an externally threaded drive spindle 15. A cylindrical hand grip forming housing 16 is internally threaded at 17 and is threaded on to the externally threaded boss 14 to rigidly mount the housing 16 to the electric motor 11.

A ball bearing, generally indicated at 18, has its outer race 19 seated in the generally cylindrical housing 16 at the end thereof opposite the internally threaded portion 17. The housing 16 is internally threaded at 20 outwardly of the bearing 18 and an externally threaded locking ring 21 is threaded therein to lock the outer race 19 into the housing 16. A stub shaft 22 is concentrically positioned in the housing 16 and has a threaded socket 23 threadably coupled to the threaded spindle 15 of the motor 11. The stub shaft 22 has a reduced

2

extension 24 forming a shoulder 25 at the juncture of the stub shaft 22 and the reduced extension 24.

The reduced extension 24 is mounted in the inner race 26 of the bearing 18 with the shoulder 25 engaging the inner end of the inner race 26.

5 The housing 16 has an externally reduced diameter at the end thereof in which the bearing 18 is mounted to permit attachment of a protection guard (not shown) thereto.

10 A circular base plate 27 is mounted on the reduced extension 24 of the stub shaft 22 and has a reduced diameter extension 28 which projects through the threaded ring 21 and engages the inner race 26 of the bearing 18 on a side thereof opposite the shoulder 25.

15 A circular cap plate 29 is also mounted on the reduced extension 24 of the stub shaft 22 outwardly of the base plate 27 but in contact therewith. The reduced extension 24 of the stub shaft 22 is threaded at 30 at its outer end and a nut 31 threaded thereon clamps the cap plate 29 against the base plate 27 and through the reduced diameter extension 28 and the inner race 26 against the shoulder 25 so that the cap plate 29 and base plate 27 revolve with the shaft 22 upon operation of the electric motor 11. A key (not shown) engages between the

20 shaft 22 and the plates 27, 29 to secure them against turning on the shaft 22. The cap plate 29 has a beveled face 32 on the side thereof opposite the base plate 27. A plurality of semi-conical sockets 33 are formed in equi-spaced relation through the cap plate 29 opening 30 through the beveled face 32 thereof. The axis of the semi-conical sockets 33 extends generally perpendicularly to the beveled face 32 of the cap plate 29 and decrease in diameter toward the base plate 27. The base plate 27 and the cap plate 29 are provided with a

25 plurality of semi-spherical sockets 34 opening into both the base plate 27 and the cap plate 29 at the bottom of each of the semi-conical sockets 33 and communicating therewith.

30 A hammer shaft 35 has a spherical head 36 on its inner end seated in the spherical socket 34 with the shaft 35 extending through the semi-conical socket 33. The conical sockets 33 opening into the beveled surface 32 limit the shafts 35 to the desired swing. The shaft 35 has a reduced diameter threaded extension 37 on its outer end and is provided with an externally toothed hammer 38 threadably engaged thereon. The spread of the hammers 38 on operation of the scaler 10 is limited by the limitation of the shafts 35.

35 In the use and operation of the invention, the motor 50 11 is held in the hand and operated by the trigger switch 13 so that the base plate and cap plate 27, 29 are rotated at a suitable speed in the neighborhood of 3000 r.p.m. The construction of the base plate 27 and cap plate 29 with the semi-spherical sockets 34 arranged in close proximity to the shaft 22 produces a scaling device 55 in which vibration is reduced to a minimum and the power required is substantially less than that of the flexible shaft operated units of the prior art devices.

Having thus described the preferred embodiment of 60 the invention, it should be understood that numerous structural modifications and adaptations may be resorted to without departing from the scope of the appended claims.

65 What is claimed is:

1. A rotary scaling device comprising a portable electric motor including a gear box at one end thereof, a cylindrical housing detachably secured to the gear box end of said motor, a spindle projecting from the gear box end of said motor into said housing, a stub shaft journaled for rotation in said housing and secured to said spindle for rotation thereby, a base plate mounted

on said shaft, a cap plate mounted on said shaft in opposed relation to said base plate, means clamping said cap plate against said base plate, said cap plate and said base plate having a plurality of semi-spherical sockets formed therebetween with said cap plate having a plurality of semi-conical sockets extending therethrough communicating with said semi-spherical sockets, a plurality of hammer shafts, a spherical head formed on each of said hammer shafts and mounted in said spherical sockets with said hammer shafts extending through said semi-conical sockets, and a hammer head detachably secured to each of said hammer shafts at the end thereof opposite said spherical head.

2. A device as claimed in claim 1 wherein said hammer heads are provided with a plurality of external teeth

arranged in circumferentially spaced apart relation thereabout.

5 3. A device as claimed in claim 1 wherein said cap plate has the face thereof opposite said base plate beveled with said semi-conical sockets opening through the beveled portion of said cap plate.

10 4. A device as claimed in claim 3 wherein said semi-conical sockets limit the spread of said hammer shafts in a position with their axis extending substantially perpendicularly to the beveled surface of said cap plate.

5 5. A device as claimed in claim 4 wherein a roller bearing is positioned between said stub shaft and said cylindrical housing supporting said stub shaft in said cylindrical housing for rotation therein.
